ADOLPHUS G. PEINE, OF CHICAGO, ILLINOIS, ASSIGNOR TO ALFRED DECKER & COHN, OF CHICAGO, ILLINOIS, A COPARTNERSHIP COMPOSED OF ALFRED DECKER, ABRAHAM COHN, AND ADOLPHUS G. PEINE.

TROUSERS SAFETY-POCKET.

1,310,210.

Specification of Letters Patent. Patented July 15, 1919.

Application filed April 1, 1918. Serial No. 226,107.

To all whom it may concern:

Be it known that I, ADOLPHUS G. PEINE, a citizen of the United States of America, and resident of Chicago, county of Cook, 5 and State of Illinois, have invented a certain new and useful Improvement in Trousers Safety-Pockets, of which the following is a specification.

The trousers pockets, as ordinarily made, 10 are only fastened at their upper ends, so that each pocket hangs loosely at its lower end, and at its sides, which makes it easy to pull the pocket out or turn it wrong-side-out. Pickpockets take advantage of this, 15 as is well known, and make a practice of securing the contents of the pockets by deftly turning the pocket wrong-side-out, in a way that does not attract the attention of the wearer, and instead of inserting the hand 20 in the pocket far enough to grasp the contents. This method of picking pockets by turning the pockets wrong-side out is followed more particularly with respect to paper money, as a roll of bills can be very 25 easily obtained this way, by simply drawing the pocket out a little, and without turning it entirely wrong-side-out. Such manipulation of the pockets, by a skilful pickpocket, does not attract the attention of the wearer, 30 as is well known, and avoids the necessity of inserting the hand into the pocket, to grasp the contents, which would be sure to attract the attention of the wearer.

The object of the invention is, therefore, 35 to provide an improved construction and arrangement whereby the pocket cannot easily be turned wrong-side-out, and whereby this method of picking pockets will be prevented, but without materially increasing the cost 40 of manufacture, and without departing to any great extent from the approved methods of tailoring.

To these and other useful ends, therefore, the invention consists in matters hereinafter 45 set forth and claimed, and shown in the accompanying drawings, in which:

Figure 1 is a perspective showing the lower portion of a figure with a pair of trousers having a pocket embodying the 50 principles of the invention.

Fig. 2 is a detail view showing the inside of the trousers, and illustrating the method of attaching the rear edges of the sack-like

pocket to prevent it from being turned wrong-side-out.

55

Fig. 3 is an enlarged detail section on line 3—3 in Fig. 2.

As thus illustrated, the invention comprises a pair of trousers constructed and tailored in the usual form, with leg portions 60 1 and a waist portion 2 of any suitable character. The sides of the trousers are provided with openings 3, of the usual form, for the so-called side pockets of the trousers. In a general way, these pockets are formed in the 65 usual manner by sack-like members 4 which are secured at their upper ends to the waistband and around the edges of the openings 3, so that each pocket hangs like a sack inside of the trousers. It will also be seen 70 that these pockets are disposed in front of the side seams 5 of the trousers, and are made somewhat wider than ordinarily is the case, so that the rear edges 6 of the pockets extend downward along the side seams 5 of 75 the trousers, and are then rounded off at 7 before extending horizontally to the corner 8 formed by the intersection of the front and bottom edges of the pocket. As usually made, a pocket of this kind could very easily 80 be pulled out through the opening 3 and turned completely wrong-side-out; but, in accordance with the invention, the lower end portion of the pocket is fastened in place, and this is preferably accomplished by 85 stitching the rear edges 6 of the pocket to the in-turned cloth of the side seam 5, at 9 and farther up at 10, so that this stitching will not show on the outside of the garment. Thus fastened in place, the pocket cannot be 90

pulled upward by a pickpocket, in the manner previously described, which is usually accomplished by deftly inserting two fingers in the pocket opening and grasping the cloth of the inner side of the pocket, and by then 95 gradually hitching or pulling it upward until the roll of bills is within reach. The stitching 10, of course, is ordinarily employed, but not in combination with the lower stitching 9, and the latter does not 100 show on the outside of the garment; but the stitching 10 can form a reinforce for the lower end of the pocket opening 3 and may show on the outside of the garment. In practice, it is found that the location of the 105 stitching or tacking 9 about three inches

below the stitching 10 is sufficient to defeat the efforts of the pickpocket, but it will be understood, of course, that the point of attachment for the lower end portion of the 5 pocket can be of any suitable character and located in any suitable or desired position. With the construction shown and described, however, the stitching or tacking 9 serves the purpose, for in practice it is found that 10 while the pocket can be drawn outward and turned wrong-side-out, to a certain extent, still this is rendered so difficult by the stitching or tacking 9 that the method employed by the average pickpocket is practically rendered impossible or ineffective.

It will be seen, therefore, that the ordinary or approved methods of tailoring are followed, so far as the general form and construction of the pocket is concerned, so that 20 manufacturing methods are not disturbed or upset to any extent whatever, and the additional stitching or tacking 9, and the change

in the size or shape of the pocket to bring the rear edge 6 over the side seam 5, does not in any way interfere with the approved 25 practice or materially increase the cost of manufacture.

What I claim as my invention is:

In trousers, a pocket (4) having the usual opening (3) therefor at the side of the 30 trousers, a fastening (10) for securing the rear edge of the pocket to the side seam of the trousers at the lower end of said opening (3), the front edge of the pocket being free, and a fastening (9) below and spaced 35 from said fastening (10) securing said rear edge to the in-turned cloth of said side seam (5), thereby to render it difficult for a pick-pocket to pull the pocket wrong side out. 40

Signed by me at Chicago, Cook county, Illinois, this 13th day of March, 1918.

ADOLPHUS G. PEINE.
